(57) **CLAIM**

The ornamental design for a wallet, as shown and described.

DESCRIPTION

FIG. 1 is a perspective view of a wallet;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a bottom plan view thereof;

FIG. 7 is a top plan view thereof;

FIG. 8 is a perspective view thereof with the flap opened;

FIG. 9 is a front elevational view thereof with the flap opened;

FIG. 10 is a rear elevational view thereof with the flap opened;

FIG. 11 is a right-side elevational view thereof with the flap opened;

FIG. 12 is a left-side elevational view thereof with the flap opened;

FIG. 13 is a bottom plan view thereof with the flap opened;

FIG. 14 is a top plan view thereof with the flap opened; and,

FIG. 15 is a top plan view thereof with the flap removed to show the design inside the wallet.

The broken lines on the surface of the wallet represent stitching.
